UNITED STATES PATENT OFFICE.

ALONZO FERNANDO HASSY, OF NEW ORLEANS, LOUISIANA.

GUARDED CASTER.

No. 823,408.

Specification of Letters Patent.

Patented June 12, 1906.

Application filed October 4, 1905. Serial No. 281,293.

To all whom it may concern:

Be it known that I, ALONZO FERNANDO HASSY, of New Orleans, parish of Orleans, State of Louisiana, have invented certain new 5 and useful Improvements in Guarded Casters, of which the following is a specification.

The object of my invention is to produce a caster which may be applied to any article of furniture having legs—such, for example, as 10 bedsteads, refrigerators, tables, chairs, and the like—and which is provided with an insect-guard that is shaped to constitute a finish for the leg to which it is adapted to be applied and which is adjustable with reference 15 thereto, so as to preserve the symmetry and finish of a castered article without impairment of its efficiency as an insect-guard.

In the accompanying drawings, which constitute a part of this application, Figure I is a 20 side elevation of one form of embodiment of my invention applied to the leg of a piece of furniture of which the lower end appears. Fig. II is a diametrical vertical section of the subject-matter of Fig. I, partially in elevation. Fig. III is a view similar to Fig. II, 25 showing a slight modification of the caster-socket and showing the guard adjustable upon the socket instead of upon the caster-shank, as shown in Fig. II.

Referring to the numerals on the drawings, 30 1 indicates the end of a leg, which is presented as a representative of the leg of any piece of furniture and which is provided with the usual socket-piece, (indicated by the numeral 2 in Fig. II of the drawings and by the numeral 3 in Fig. III of the drawings.) The socket-piece accommodates a shank, (indicated by the numerals 4 in Fig. II and by the numeral 5 in Fig. III.) The difference between 35 40 the socket-pieces 2 and 3 is that the former ends flush with the end of the leg and the latter projects below the same. The shank 4 or 5 carries a caster 6, which may be swiveled to the shank upon the reduced end 7 in the usual 45 manner and provided with a roller 8. Any preferred form of caster may be employed.

My invention consists in providing the caster with a guard 10, which is provided with a corrugated inner wall 11. It may be 50 threaded to the shank of the caster, as indicated in Fig. II of the drawings, or it may be threaded to the socket 3, as indicated in Fig. III thereof. The illustration afforded in Figs. II and III is designed to indicate that 55 the guard 10 is generally adjustable to and from the end of the leg without special re-

gard to the particular member which carries it. The guard is provided with an abutment-screw 14, by means whereof it may be fixedly secured in any position with reference to the 60 end of the leg to which it may be adjustable. The important feature of my invention is in providing a guard member which may be employed to constitute unobstructively and unobtrusively a finish to the end of the leg 65 to which it is attached. Heretofore insect-guards have been objectionable in use upon ornamental furniture because they were too obtrusive, if not ostentatious in appearance. By my invention the guard may be adjusted 70 to such close propinquity to the end of the leg to which it is attached as to be scarcely detectable and at the same time to afford complete protection against insects, which in 75 some climates are exceedingly pestiferous.

In practice the legs of the article to be equipped with my invention are fitted with casters of suitable size and each having a guard of proper dimensions. The employment for that purpose of a socket-piece is 80 preferably for the security it affords in mounting the shank in the end of the leg, as well as for the freedom of movement which it affords to the shank when inserted into it. The guard is then adjusted to the required 85 distance from the end of the leg and is secured in place by the abutment-screw 14. The guard is, as illustrated, a cup-like receptacle, adapted to contain a liquid, preferably of viscous consistency, which will serve to 90 entrap any insect that enters the interior of the guard. The corrugated wall with which the interior of the guard is finished has a tendency to prevent escape of the liquid in the ordinary movement of furniture from 95 place to place. The outside of the guard, besides being made of dimensions to correspond to the leg to which it is applied, may be painted or otherwise finished in imitation of the material of which the leg is made.

100 What I claim is—

The combination with a caster provided with a cup-shaped insect-guard having a corrugated internal wall, said wall being adapted to confine a liquid.

105 In testimony whereof I have hereunto signed my name in the presence of two subscribing witnesses.

ALONZO FERNANDO HASSY.
